UNITED STATES PATENT OFFICE.

GEORGE GROVER, OF SOUTH NORWALK, CONNECTICUT, ASSIGNOR OF ONE-HALF TO
JAMES DELOHERY, OF DANBURY, CONNECTICUT.

MACHINE FOR SCALDING FUR-NAPPED BODIES.

Application filed April 18, 1922. Serial No. 555,143.

To all whom it may concern:

Be it known that I, GEORGE GROVER, a citizen of the United States, residing at the city of South Norwalk, in the county of 5 Fairfield and State of Connecticut, have invented certain new and useful Improvements in Machines for Scalding Fur-Napped Bodies; and I do declare the following to be a full, clear, and exact description of the invention, such as will enable others skilled in the art to which it appertains to make and use the same.

This invention relates to machines for scalding fur napped bodies.

15 In the art of making fur napped hats, a substantial felt body is used as a base and on this loose fur particles are distributed which are firmly united to the body by the application of hot water and intermittent 20 kneading processes.

Heretofore these bodies, with the fur stuck thereon by an initial application of hot water and hand pressure, are preferably rolled into bundles encased in any suitable 25 thin cloth; and are then subjected to the action of felting or sizing rolls, which latter are provided with exterior lags whereby the proper kneading process is applied to the hats, and these hat bundles are frequently 30 dipped in the scalding water and subjected to this felting process quite a number of times.

While the above process is commonly applied and is preferable with respect to the 35 ordinary fur hats which are formed completely by this felting or sizing process, nevertheless in the instance of fur napped hats this process is so slow and requires so much attention that it is quite expensive, 40 and it is the object of the present invention to produce a structure whereby fur napped hats may be treated most expeditiously and also greatly improved in the uniformity of the napped surface.

45 Furthermore, this invention contemplates an entirely new process in the scalding and felting of fur napped bodies, and consists broadly in tumbling these bodies within perforated closed cylinders that have lags extending from the interior walls thereof, 50 the cylinders having no axial movement, but being carried orbitally so as to be intermittently submerged within and emerged from the scalding water in the tub, the 55 water readily entering the perforations in

the cylinders when the latter are submerged, and just as readily draining out of the cylinders when the latter rise out of the water.

There are a plurality of these cylinders that are arranged around the shaft of the 60 machine and are rigid therewith so that they are carried by the revolution of the shaft, and the partially formed hats within the cylinders are constantly being scalded and tumbled against the lags, and this is 65 repeated until the felting process is completed.

In order that the statements made above may more readily be understood and appreciated, a description of the invention will 70 now be given in more or less detail, with especial reference to the drawings which form a part of this application and which show one form in which the invention is exemplified.

75 Referring to these drawings—

Figure 1 is a side elevation of a machine which is particularly adapted for carrying out this invention;

Figure 2 is a central longitudinal section 80 of the machine;

Figure 3 is a front elevation; and

Figure 4 a detail sectional elevation of one of the cylinders.

Similar numerals of reference denote like 85 parts in the several figures of the drawing.

1 is the frame of the machine and 2 any suitable scalding tub secured thereto. 3 is a shaft journaled on the frame and having keyed thereon the cheek pieces 4.

90 5 are hollow cylinders preferably made of wood which are secured at their ends to the cheek pieces 4 and surround the shaft 3, so that it will be clear that, as the shaft revolves, these cylinders will be carried 95 around orbitally, or, in a circular path around said shaft.

Each cylinder has a door 6 which is secured in closed condition in any suitable manner, as, for instance, by a hasp 7 on the door, a perforated stud 8 projecting from the cylinder, and a pin 9, the latter being inserted through the perforated stud after locking engagement with the hasp.

100 Each cylinder, including its door, is perforated at numerous locations, as shown at 10, and from the inner wall of each cylinder and door longitudinally disposed lags 11 of wood project.

105 While it is preferred to have these lags 110

extend lengthwise of the cylinders, any style of lags disposed in any suitable manner may be employed.

The tub is supplied with scalding water 5 in the manner usual in hat felting machines, and, as the shaft revolves, the cylinders will be submerged within and emerged from the water, the latter entering and draining through the perforations 10.

10 The felt bodies coated with fur by the usual initial "sticking" process, are either bundled within a suitable cloth and cast into the cylinders, or such bodies may be placed in the cylinders with no cloth covering whatever, and, during the revolution of the shaft, said bodies will be tumbled around the cylinders and against the lags, and alternately saturated with hot water and drained thereof, and this process continues until the felting is completed.

Napped hats treated by this process are superior in every respect. The fur is more closely and uniformly felted, and, moreover, the machine is a great saver of labor.

25 Having thus described this invention what is claimed is:—

1. In a machine for scalding napped felt bodies, a scalding tub adapted to contain water at suitable temperature, a frame supporting the tub, a rotary shaft journaled on the frame, and a series of hollow perforated cylinders carried by said shaft in radial disposition thereto and provided with internally projecting lags, said cylinders during their orbital travel around said shaft being continuously submerged within and emerged from the water in the tub.

2. In a machine for scalding napped felt bodies, a frame, a scalding tub supported thereby, a rotary shaft journaled on the

frame, and a series of hollow perforated cylinders having internally projecting lags and carried by said shaft in radial disposition thereto, said cylinders being each provided with perforated doors likewise having lags projecting from their interior surfaces.

3. In a machine of the character described, the combination of a frame, a scalding tub supported thereby, a shaft journaled on said frame, and a series of hollow perforated cylinders carried by said shaft and arranged in radial circular disposition thereto, each cylinder having internally projecting lags and a perforated door likewise having internally projecting lags, the napped felt bodies being placed within the cylinders and the doors closed and thereafter the cylinders being dipped during their rotation within the scalding water in the tub.

4. In a machine of the character described, a frame, a scalding tub supported thereby, a shaft journaled in said frame, and a plurality of perforated hollow cylinders orbitally surrounding said shaft and rigid therewith and having no independent axial movement, the cylinders having internally projecting lags and being carried by the rotation of the shaft so as to submerge within and emerge from the scalding tub, while each cylinder has a door.

5. The herein-described process of scalding napped fur bodies, which consists in tumbling them within hollow perforated orbitally revolved cylinders having no axial revolution and provided with internal lags, and intermittently and continuously subjecting said bodies to scalding and draining.

In testimony whereof I affix my signature hereto.

GEORGE GROVER.
